DESIGN FOR A TEXTILE FABRIC

Samuel E. Staines, Allendale, N. J., assignor to
Botany Worsted Mills, Passaic, N. J., a corpora-
tion of New Jersey

Application October 1, 1938, Serial No. 80,172

Term of patent 3½ years

To all whom it may concern:

Be it known that I, Samuel E. Staines, a citizen of the United States, residing at Elmwood Avenue, Allendale, in the county of Bergen and State of New Jersey, have invented a new, original, and ornamental Design for Textile Fabrics, of which the following is a specification, reference being had to the accompanying drawing, forming part thereof.

The figure of the drawing is a plan view of

a piece of textile fabric showing my design.

The design of this invention is characterized by raised portions of the weave presenting the appearance of roots with rootlets associated therewith.

I claim:

The ornamental design for a textile fabric, as described and shown.

SAMUEL E. STAINES.
